METAL SHEARING MACHINE AND THE LIKE

Alfred Edward Cartlidge, Wokingham, England

Application November 6, 1946, Serial No. 708,059

In Great Britain May 23, 1946

8 Claims. (Cl. 164—43)

1

This invention relates to metal shearing machines and the like more particularly of the nibbling type.

The object of this invention is to provide a machine which will shear metal or other material of flat or intricate shape or the interior parts of such metal in a quick and efficient manner.

A further object is to provide means whereby the machine can be readily adjusted during running to take work of various thicknesses.

With these and other objects in view the invention consists in providing a shearing, riveting, punching or like machine comprising a pair of longitudinal members pivoted together at an intermediate position, one end of said pair of members providing jaws fitted with co-operating operating members, one member at the other end having rotatably mounted therein a shaft having a cam or eccentric on which is mounted a sleeve member having a ball-like extension projecting into a recess formed in a block slidably mounted in an inclined guide or recess in the other longitudinal member and lever means to move the sleeve member and its co-operating block against the action of spring means whereby the co-operating members will be held in a spaced and non-operative position to enable work to be inserted between the jaws. The said lever is preferably so mounted and arranged as to positively hold the jaws out of operative position in one position of the lever or to permit of operation when in its other position.

This invention also consists in providing means for the adjustment of the block in its inclined guide or recess whereby the spacing of the jaws may be varied to operate efficiently on work of various thicknesses.

The invention further consists in so arranging the lever means that the jaws can be positively held out of operative position during the running of the machine and the means for adjustment to take work of various thicknesses may also be operated during running.

The invention will now be described with reference to the accompanying drawing in which:

Fig. 1 shows by way of example an elevation of one form of shearing machine constructed according to this invention;

Fig. 2 is a longitudinal sectional elevation thereof showing the jaws opened for receiving work to be cut interiorly;

Fig. 3 is a cross section taken on the line a—a of Fig. 1 and

Fig. 4 is a detail front perspective view of the cutters.

As shown the improved shearing machine comprises a base member in the form of a longitudinal arm 1 having intermediately of its ends upstanding spaced ears 2 adapted to carry a fulcrum 3 for a further arm member 4 of substantially similar length to the lower arm 1. The

2

lower arm or base 1 is formed with means such as apertured lugs or the like 5 whereby it may be bolted to a bench or other support. The forward projecting portions of the arms 1 and 4 which provide jaws 6 and 7 are fitted with cutting or shearing members 8 and 9 respectively having cutting edges arranged substantially at right angles to the said arms. The lower cutting member 8 which is secured in the lower jaw 6 is of substantially square shape in cross section and formed with an upstanding nose 10 having a curved or convex cutting edge 11 on its inward end as shown more particularly in Fig. 4. The upper cutting member 9 which is preferably adjustably mounted in the upper jaw 7 is formed with a depending nose 12 of curved or angular shape. The arrangement is such that the co-operating cutting members 8 and 9 provide a point or curved contact arranged centrally of the longitudinal cutting members. Thus providing for efficient shearing operation upon the downward movement of the upper cutter 9 in relation to the lower fixed cutter 8 in the manner to be hereinafter described. The cutters 8 and 9 are so shaped as to permit of intricate shearing and as the upper cutter 9 is moved at a high speed shearing can be performed in a quick and efficient manner by a nibbling action. The rear end of the longitudinal or base member 1 is formed with upstanding lugs 13 which are fitted with antifriction bearings 14 for a shaft 15 arranged at right angles to the base member 1. This shaft 15 is fitted with a pulley 16 and is adapted to be rotated by suitable power means but if desired the shaft may be manually operated. This power shaft 15 is formed or provided with an eccentric portion 17 on which is mounted an antifriction bearing 18 carrying a sleeve member 19 having a ball like extension 20. This ball like extension 20 is adapted to co-operate with a block member 21 slidably mounted in an inclined recess or guide groove 22 formed or provided in the under surface of the upper arm member 4. Conveniently this block member 21 is formed with a part spherical recess of less than a hemisphere in shape so that the ball member 20 can co-operate therewith. The block 21 is preferably freely slidable in the guide or recess 22 in the arm member 4 and is held in position against removal by the ball member 20 and by spring means connecting the outer arms 1 and 4 of the machine. Conveniently the upper arm 4 is formed with an aperture 23 for a threaded rod 24 having at its end a hook 25 for connecting with the end of a coiled tension spring 26 secured in an aperture in the base conveniently by a cross bar 27 mounted in the lower edge of the base. This threaded rod 24 is held in adjustable position by a wing nut 28 abutting on the upper arm 4 so that the tension of the spring 26 can be readily adjusted. In order to raise the upper arm 4 out of operative position so

that work can be inserted for interior shearing the sliding block 21 is adapted to be moved longitudinally in its inclined guide-way 22 by means of a lever member 29. The lower end of this lever 29 has a fulcrum on a pin 30 extending from the base and adjacent to the fulcrum the lever 29 is fitted with an apertured swivel lug 31 for the connection at one end of a connecting rod 32 which is connected at its other end to the sleeve member 19 through the medium of a further apertured swivel lug 33. The connecting rod 32 is screw threaded at each end and fitted with lock nuts 34 for adjustment purposes. The block 21 is adjustably mounted in its guide by means of an adjusting screw 35 fitted in the end of the upper arm 4. The end of this adjusting screw 35 is adapted to contact normally with the end of the block 21 and thus limit its movement in an outward direction. Conveniently the adjusting means comprise a milled headed screw 35 screwed into the end of the arm 4 and adapted to be held in a locked position by a lock nut 36. The sliding block 21 is held normally against the end of the adjusting screw 35 by spring means such as a coiled spring mounted within a guide, but preferably by a coiled tension spring 37 connected at one end to the sleeve member 19 and at its other end to a bracket member 38 carried by the lower arm or base 1. The outer end of the spring 37 is preferably connected adjustably to the bracket member 38 by means of a threaded hook 39 and an adjustable wing nut 40 having locking means 41.

In operation and when the shaft 15 is rotated at a high speed the cam 17 will rock the upper arm 4 and the upper jaw 7 will move toward and away from the lower jaw 6 so that the cutting operation will be effected when work is inserted between the jaws, and cutting members 8 and 9. The upper jaw 7 is so moved in relation to the lower jaw 6 as to provide a nibbling effect to the cutter 9. When it is desired to adjust the jaws 6 and 7 to take work of different thicknesses the adjusting screw 35 is rotated to move the block 21 in its slide 22 and the position of the block 21 will regulate the distance between the jaws 6 and 7 and the normal spacing thereof so that shearing can be effectively performed without burr. When it is desired to shear for instance the interior of a metal plate or tube the lever 29 is pulled on its fulcrum towards the operator so that the block 21 will be shifted towards the main fulcrum 3 of the machine as shown in Figure 2 and thus the outer jaw 7 will be raised to permit of the work to be inserted between the cutting jaws. The arrangement is such that the lever 29 is moved past the dead centre so that the block is held in its adjusted position, thus the cutter 9 in the upper jaw 7 is prevented from engaging with the co-operating cutter 8 in the lower jaw 6 so that the work can be inserted. When the lever 29 is moved back the sliding block 21 will be moved back by the spring means 37 so that it engages the adjusting screw 35 as shown in Figure 1 and the shearing will take place. It will be seen that the adjustment of the jaws 7 and 8 to take work of various thicknesses and the raising and lowering of the upper jaw 7 to permit the work to be inserted therebetween for shearing can be effected whilst the machine is running as the upper arm 4 moves to a very small degree.

Although the invention is more particularly described in connection with a shearing ma-

chine it will be understood that the shearing elements 8 and 9 may be replaced by other tools such as forming or beading tools or turning over and flanging tools or riveting or punching tools.

5 What I claim is:

1. A metal working machine comprising a pair of longitudinal members pivoted together at an intermediate position, one end of said pair of members providing jaws fitted with co-operating members, one member at the other end having rotatably mounted therein a shaft having a cam means on which is mounted a sleeve member having a ball like extension projecting into a recess formed in a block slidably mounted in an inclined guide in the other longitudinal member and lever means to move the sleeve member and its co-operating block against the action of spring means, whereby the co-operating members will be held in a spaced and non-operative position to enable work to be inserted between the jaws.

2. A machine as claimed in claim 1 wherein the lever is so mounted and arranged as to positively hold the jaws out of operative position in one position of the lever or to permit of operation when in its other position.

3. In a machine as claimed in claim 1 the provision of means for the adjustment of the block in its inclined guide whereby the spacing of the jaws may be varied.

4. A machine as claimed in claim 1 wherein means are provided for the adjustment of the jaws to take work of various thicknesses, the said means being so arranged as to be operated during the running of the machine.

5. A machine as claimed in claim 1 wherein the block is formed with a part spherical recess of less than a hemisphere in shape for the reception of the ball like extension of the sleeve member.

6. A machine as claimed in claim 1 wherein the block is freely slidable in the guide or recess and held against removal by the ball like extension and by spring means connecting the upper and lower longitudinal members of the machine.

7. A machine as claimed in claim 1 wherein the sliding block is held normally against adjusting means by a coiled tension spring connected at one end to the sleeve member and at its other end to a bracket member carried by the sleeve supporting longitudinal member.

8. A machine as claimed in claim 1 wherein the spring means comprise a coiled tension spring connected at one end to the sleeve member and at its other end to a bracket member carried by the sleeve supporting longitudinal member.
